VOLUTE SPRING

Cal W. Wulff and Frank G. Newman, Chicago, Ill.,
assignors to Holland Company, a corporation of
Illinois

Application May 12, 1950, Serial No. 161,706

13 Claims. (Cl. 267—62)

1

This invention relates to volute springs, either of the type designed with built-in absorption to carry live loads, or of the type designed to act as snubbers with other parallel mounted springs carrying major portion of the load.

The primary object of the invention is to provide a spring of these types which has superior damping properties and characteristics when compared with volute springs now in use, and which because of their built-in absorption characteristics are capable of absorbing vastly greater work energy over their effective life cycle than prior art volute springs of comparable dimension and material.

These and further objects and advantages will become apparent as the disclosure proceeds and the description is read in conjunction with the accompanying drawings, in which

Figure 1 is a side elevational view partly in section showing a volute snubber spring made in accordance with this invention, the spring being shown at its free height after being given a cold set;

Figure 2 is a plan view of the same with the dead coils being indicated by distinctive cross-hatching;

Figure 3 is a side elevational view of the spring shown in Figures 1 and 2 but shows the form of the coil as wound, and before being given a cold set;

Figure 4 (subdivided into Figures 4a to 4e inclusive) shows the profile "as coiled slope" of the developed bar for various types of volute springs, as indicated by suitable legends; and

Figure 5 is a graph showing, in comparison with a conventional tight-wound volute spring, the load-deflection characteristics (both on compression and release) of a volute spring made in accordance with this invention.

It should be understood that the selection of a particular volute spring for illustration in the drawings and specific description in the specification is for the purpose of complying with section 4888 of the revised statutes and should not be construed as imposing limitations on the appended claims, except as may be required by the prior art.

The design theory of volute springs is not too well known and the fact is that in considering volute spring formulas there are, in addition to the primary torsional stress produced by a central load, many secondary stresses which arise out of the variation of the twisting torque from section to section, by flexibility of the dead coils and by misalignment of the spring seats. By

way of example, cone and arch stresses are typically secondary stresses.

The friction developed in volute springs has always been considered more or less undesirable because of its effect on fatigue endurance. As a matter of fact, volute spring designs for use as load-carrying springs have normally avoided contact between adjacent coils because experience demonstrated that the contacting surfaces were non-uniform, with the result that gouging occurred, producing excessive wear and accelerated failure.

We have found that instead of avoiding frictional contact between the adjacent active coils of a volute spring, we can provide a volute spring of substantially greater work-absorbing capacity by building certain frictional adsorption forces into the spring and controlling its characteristics so that the frictional forces are substantial, are evenly spread over wide areas, will not be effectively lost as the spring wears, and which provide volute spring characteristics never before attained. Essentially, our spring is a non-harmonic snubber spring in which energy absorption through friction is of greatest importance.

This is accomplished by employing what we term negative helix angle when winding the volute spring while hot. By "negative helix angle" is meant a developed bar whose profile before setting curves upwardly from outer active coil to inner active coil. In other words, the helix angle increases from outer active coil to inner active coil in the as-coiled condition and before cold set. The advantages of this negative or increasing helix angle may best be understood by referring to Figure 4 and the graphs therein shown.

As is well understood, in every volute spring a certain portion of the outer coil and a certain portion of the inner coil are inactive in so far as their load-carrying capacity is concerned, and these coils or portions of coils are commonly called dead coils. The intermediate turns or coils of the spring are active coils and usually they include an outer active coil, a middle active coil and an inner active coil.

In order to distinguish our improved volute spring from those heretofore known, one may refer to Figures 4a to 4e inclusive which compare the "as coiled" slope of developed bars having various helix angles and pitch characteristics.

First consider Figure 4a. The graph line 10 is a straight line and for that reason the spring may be said to have a constant helix angle. However, it will be seen that the axial pitch in-

dicated by the lines $11a$, $11b$ and $11c$ diminish from the outer active coil to the inner active coil. The result is that when the spring is deflected to solid, the active coils are non-uniformly stressed, with the result that the maximum efficiency of the spring material is not fully attained.

For this reason some manufacturers make what is known as a spring having a positive helix angle, as shown by the profile graph line 12 in Figure 4b. Here it will be seen that the profile of the developed bar as coiled curves downwardly from outer active coil to inner active coil. In this case the axial pitch decreases, as in the case of the constant helix angle coil illustrated in Figure 4a, but the pitch indicated by the lines $13a$, $13b$ and $13c$ diminishes at such a rate in progressing from the outer active coil to the inner active coil that all sections of the active spring are stressed uniformly at solid.

It is possible to build other desired characteristics into volute springs using a positive helix angle such as shown by the graph line 14 in Figure 4c, and in this case the axial pitch indicated by the lines $15a$, $15b$ and $15c$ decrease at some rate which does not produce uniform stress at solid.

It has always been considered undesirable to attempt to pitch a volute spring with a negative helix angle because such a pitching of the coils would accentuate the non-uniform stressing of the coils at solid. We have found, however, that by giving the coils a negative helix angle, we can build into the coils certain frictional forces which far outweigh in importance the apparent though not real disadvantage of non-uniform stressing of the coils. For example, in Figure 4d there is indicated by the graph line 16 the profile of a developed bar as coiled, and in this case the pitch, indicated by the lines $17a$, $17b$ and $17c$, is constant. This means, of course, that at solid the inner active coil will be more severely stressed than the middle active coil, and this latter coil will in turn be more highly stressed than the outer active coil.

This condition may be accentuated still further by providing not only a negative helix angle but also a negative or reverse pitch, as indicated by the graph line 18 in Figure 4e. In this case the axial pitch, indicated by the lines $19a$, $19b$ and $19c$ actually increases from outer active coil to inner active coil.

Thus it will be seen that the prior art has always employed either a constant helix angle or a positive helix angle which resulted in axial pitch diminishing from outer active coil to inner active coil, whereas in our improved design a negative helix angle is used which ordinarily results in either a constant axial pitch or a reverse pitch, the latter pitch being defined as one that increases from outer active coil to inner active coil.

Let us consider now a volute spring that is wound to provide a reverse pitch, negative helix angle in the "as coiled" condition. Such a spring is shown in Figure 3 and the outer dead coil is indicated at 20 , the inner dead coil at 21 , the outer active coil at 22 , the middle active coil at 23 and the inner active coil at 24 . Although it is not possible to accurately see the negative helix angle in this figure, it is easy to see that the coil has reverse axial pitch, i. e., the inner active coil is more greatly pitched than the middle active coil 23 , and this latter coil is more greatly pitched than the outer active coil 22 .

By way of example, volute springs constructed

in accordance with this invention and made of C1085 spring steel may be coiled at about 1800° F. (which is well above the critical temperature for this particular material) and then quenched, after which the springs are tempered by reheating to a temperature of about 750° F., the precise temperature being determined by the ultimate physical properties desired. When, after tempering, the spring is given a cold set, i. e., compressed to solid and then released and vibrated to find its true free height, it will be found that the elastic transformation of the steel that has taken place on cold setting gives it a pitch somewhat as shown in Figure 1. In other words, on cold setting trapped stresses are set up within the material itself which have an important bearing on fatigue endurance. The particular pitch for the coils of the finished spring will depend upon the materials used, smoothness of the material, etc., but it will be found that when the spring in its coiled condition is given a particular coil pitch relationship, the free height of the finished spring will be the same for any given spring material (assuming uniform manufacturing procedures).

For example, let us assume that a steel bar $5\frac{3}{4}$ " wide, $.343$ " thick is tightwound when hot on a substantially cylindrical mandrel to provide a $5\frac{1}{2}$ " outside diameter for the spring, and that while winding the active coils are pitched progressively (from outside active coil to middle active coil to inside active coil) from $.937$ " to 1.56 " to 1.75 ", respectively. If a C1085 spring steel is used, this spring upon cold set will assume an axial pitch which from outside active coil to inside active coil progresses approximately from $.62$ " to $.68$ " to $.70$ ", respectively. If steel used is A9262 spring steel, the axial pitch of the finished spring will progress approximately from $.68$ " to $.75$ " to $.81$ ", respectively, from outside active coil to inside active coil.

As stated before, the springs, after coiling, and before being given their cold set are heat treated according to particular requirements, and one of the advantages of the reverse axial pitch is that it exposes more of the friction surface to the desired heat treatment before the spring is given its cold set, thereby improving the physical properties of the spring itself. Furthermore, the exposure of greater areas of the inner and middle coils for heat treatment is fortuitous because surface and depth hardness are of extreme importance.

The particular axial pitch given to the several active coils is determined by the end characteristics desired but, generally speaking, the inner active coil is designed so that when the spring is given its cold set it will be stressed almost to maximum capacity of the material and the middle active coil will be stressed somewhat less with the outer active coil being stressed very lightly during the cold set. The result is that the outer active coil together with the outer dead coil acts as a resilient casing for the middle and inner active coils during their deflection, and the constant or increasing pitch given to the active coils, as coiled, tends, upon cold setting, to pack the inner active coil tightly into the middle active coil, and the middle active coil tightly (although slightly less so) into the outer active coil, with the result that there is an inherent radial pressure exerted between the active coils which maintains them in tight frictional contact throughout the life of the spring, that is, each active coil is contained under positive radial compression within its adjacent outer coil.

It has been found empirically that even when springs made in accordance with our invention wear, they lose little of their frictional absorption characteristics due to this inherent radial pressure created by the reverse axial pitch built into the spring when tightwound and coiled hot and subsequently cold pressed.

There is another factor which is believed to be partially responsible for the improved energy absorption characteristics of springs made in accordance with our invention. It can be established mathematically that when volute springs are given a positive helix angle, as is conventional (i. e. a decreasing helix angle from outer active coil to inner active coil), they have a pronounced tendency to "cone" which produces a secondary stress in the spring and which tends to produce gouging due to the uneven contact between adjacent turns of the spring brought about by non-axial eccentric loading. When, however, the spring is wound with a negative or increasing helix angle, this "coning" effect diminishes, with the result that there is a more uniform contact between adjacent turns of the volute and diminished eccentricity on loading, which thereby distributes the friction forces more evenly, and prevents the gouging that causes excessive wear and rapid loss of absorption.

This diminished "coning" effect taken in conjunction with the built-in radial pressure from inner active coil to middle active coil, and from middle active coil to outer active coil gives the spring an unusually high capacity to absorb energy, particularly at small spring deflections where it has been unusually difficult in the past to provide for such energy absorption.

This is indicated in Figure 5 which shows a load deflection curve, both on compression and release, for a spring made in accordance with our invention—this in comparison with a conventional tightwound volute spring of equivalent dimension and material. For clarity, the characteristic curve for the improved spring made in accordance with this invention is shown in full lines, whereas the characteristics of a conventional spring are indicated in dotted lines.

As is well known, the area under a compression curve is a measure of the work done or energy expended in deflecting the spring. The area under the release curve represents the work expended by the spring in returning to its original free height against a resisting load. In all springs, and particularly snubber springs, the work expended by the spring in returning to its free height will be less than the work expended in compressing the spring. The difference in the compression and release work is the energy or work absorbed by the spring. The compression and release curves for a given spring are commonly called the hysteresis loop for that spring, and it is essential in a snubber spring to have the area between these two curves of the desired magnitude, taking into consideration the particular application of the snubber spring. This represents the work absorbed by the spring.

In Figure 5 the compression curves of a spring made in accordance with this invention are shown in comparison with a compression curve of the conventional tightwound volute spring of equivalent dimension and material. These two curves are designated 26 and 27, respectively. The release curves for these springs are indicated at 28 and 29, respectively. In comparing the hysteresis loops over the range of deflection from free height to solid it is apparent that a

spring made in accordance with this invention has much greater energy absorption than a conventional spring of equivalent dimension and material.

This point is all the more clear when one considers the portions of the hysteresis loops which lie between spring heights of $8\frac{1}{4}''$ and $7''$ which represent the normal overall operating range. For clarity, the portion of the hysteresis loop within this range for the improved volute spring is indicated by crosshatching bounded by points A, B, C and D, and similarly the portion of the hysteresis loop for the comparable conventional tightwound volute spring is represented by other crosshatching bounded by points E, F, G and H. It is apparent that within the range indicated our improved volute spring is capable of absorbing over twice the energy which the conventional tightwound volute spring can absorb within that range. This improved energy absorption is directly attributable to each inner active coil being contained under elastic radial compression within the adjacent larger coil.

Another important feature of our invention is that compared with conventional tight-wound volute springs, the energy of absorption for our spring under small deflections will be much greater percentage-wise than at larger deflections. By comparing the portion of the hysteresis loops, for our improved spring and for the conventional spring in Figure 5 within the range of spring height of $8\frac{1}{4}''$ to $8''$, it will be noted that the absorption of energy by the improved spring is approximately four times as great as that of the conventional spring. Even more pronounced results will be observed for smaller deflections. Inasmuch as high energy absorption characteristics at small deflections is an especially desirable feature for snubber springs, it will be seen that our improved spring has exceptionally desirable characteristics for such use, and actual tests have verified the greatly improved energy absorption characteristics of the improved spring.

The spring characteristics shown in Figure 5 for our improved spring represent a spring that is designed to act primarily as a snubber, as for example, one having the pitch and helix angles specified for Figures 1 to 3 inclusive. If, instead of using a reverse axial pitch with a negative helix angle, the spring were hot wound to provide a negative helix angle with constant axial pitch, the spring would not be as effective as a snubber but more suitable as a non-harmonic load-carrying spring. It would, for example, be superior to conventional volute load springs because of its inherent frictional absorption characteristics at low spring deflections which persist throughout the effective life cycle of the spring, but would not possess the high energy absorption characteristics desirable in a spring which is mounted in parallel with other load-carrying springs for action as a snubber.

It will be understood that in manufacturing a spring in accordance with our invention, the bar from which the spring is to be made is first scarfed to provide a blank such as shown on page 361 of "Mechanical Springs" by A. M. Wahl, 1944 ed., and the spring is then tightly wound about a substantially cylindrical mandrel provided with the usual stripping taper. The bar is heated well above critical temperature, say, to about 1800° F. and tightly wound under external roll pressure about the mandrel starting with the scarfed portion of the inner inactive

coil normal to the axis of the mandrel. If no restraint or guidance is given to the bar as it is wound about the mandrel, it will have a constant free helix angle, but this angle may be changed by guiding the bar as it is wrapped around the mandrel, this being accomplished with a lead screw having the desired pitch or rate of pitch. In order to provide the ordinary positive helix angle, a lead screw is used which has increasing pitch so that the bar as it is wrapped around the mandrel is extended along the length of the mandrel. In our invention, the lead screw is, in a sense, reversed because, in order to obtain a negative helix angle, it is necessary to restrain rather than augment the distance which the spring extends itself along the axis of the mandrel during coiling. All of this will be clearly understood by those skilled in the art.

It should be understood that reference in the specification and claims to outer active, middle active and inner active coils should not be interpreted to mean that the outer active coil and the inner active coil must necessarily be a full 360° coil, because in some cases either of these two coils may be something less than 360° in extent.

We claim:

1. In a volute spring, the combination of inactive outer and inner coils and at least three active intermediate coils, all tightly wound, the outer active coil being low-stressed, the middle active coil highly stressed and the inner active coil still more highly stressed, whereby the outer active coil acts as a resilient casing to yieldably oppose unwrapping of the middle and inner active coils, said middle and inner active coils maintaining firm frictional contact with each other even after substantial wear due to the high stressing of said middle and inner active coils, and said spring being hot-wound with an increasing helix angle from outer active coil to inner active coil, and then cold set, whereby secondary stresses due to coning are attenuated.

2. In a volute spring, the combination of inactive outer and inner coils and at least three active intermediate coils, all tightly wound, the outer active coil being low-stressed, the middle active coil highly stressed and the inner active coil still more highly stressed, whereby the outer active coil acts as a resilient casing to yieldably oppose unwrapping of the middle and inner active coils, said middle and inner active coils maintaining firm frictional contact with each other even after substantial wear due to the high stressing of said middle and inner active coils, and said spring being hot-wound with an increasing axial pitch from outer active coil to inner active coil and then cold set, whereby secondary stresses due to coning are attenuated.

3. A tightly wound volute spring comprising inactive outer and inner coils and at least three intermediate active coils, said spring after being tightly wound while hot and before cold setting being characterized by having its active coils provided with constant or increasing axial pitch from outer active coil to inner active coil, whereby upon compression of the spring the inner and middle active coils expand radially outwardly more rapidly than their adjacent enveloping coils to provide a continuous radial pressure between said adjacent coils.

4. A tightly wound volute spring comprising inactive outer and inner coils and at least three intermediate active coils, said spring after being

7 tightly wound while hot and before cold setting being characterized by having its active coils provided with an increasing helix angle from outer active coil to inner active coil, whereby upon compression of the spring the inner and middle active coils expand radially outwardly more rapidly than their adjacent enveloping coils to provide a continuous radial pressure between said adjacent coils.

5. A volute snubber spring comprising inactive outer and inner coils and at least three active intermediate coils, including an active outer coil, an active middle coil, and an active inner coil, said active coils having overlapping, substantially cylindrical, working surfaces in firm, substantially uniform contact with each other and under intense inherent radial compression when the spring is at free height, whereby the spring has a relatively high energy absorption under light loads.

6. A volute snubber spring as set forth in claim 5 in which the active coils are of generally rectangular cross-sectional shape and of substantially uniform thickness.

7. A volute snubber spring as set forth in claim 5 in which the material distribution within the active coils is such that the active coils maintain firm, uniform contact with each other during deflection of the spring due to said inherent initial radial compression forces.

8. A volute snubber spring as set forth in claim 5 in which the spring in its as-coiled condition and before cold-set is characterized by an increasing helix angle whereby after cold setting the material distribution within the active coils is such that upon compression of the spring, the inner and middle active coils expand radially outwardly more rapidly than their adjacent enveloping coils to provide a continuous radial pressure between said adjacent coils as the spring is compressed.

9. A volute snubber spring as set forth in claim 5 in which said spring is hot-wound and then cold set, and in which the spring structure in its as-coiled condition before cold setting is characterized by a constant or increasing axial pitch from outer active coil to inner active coil.

10. A volute snubber spring as set forth in claim 5 in which said spring is hot-wound and then cold set, and in which the spring structure in its as-coiled condition before cold setting is characterized by an increasing helix angle from outer active coil to inner active coil.

11. In a volute spring, the combination of inactive outer and inner coils and at least three active intermediate coils, said spring being tight wound while hot with an increasing helix angle and then cold-set, whereby the outer active coil is low-stressed, the medium active coil highly stressed, and the inner active coil still more highly stressed, with the outer active coil acting as a resilient casing to yieldably oppose unwrapping of the middle and inner active coils, said spring being further characterized by relatively high inherent radial compression forces between the active coils when the spring is at free height.

12. In a volute spring, the combination of inactive outer and inner coils and at least three active intermediate coils, all tightly wound, the outer active coil being low-stressed, the middle active coil highly stressed and the inner active coil still more highly stressed, whereby the outer active coil acts as a resilient casing to yieldably oppose unwrapping of the middle and inner active coils, said middle and inner active coils

maintaining firm frictional contact with each other even after substantial wear due to the high stressing of said middle and inner active coils, and said spring being hot-wound with an increasing helix angle from outer active coil to inner active coil, and then cold set, said active coils after cold setting being under relatively high, continuous, radial compression.

13. In a volute spring, the combination of inactive outer and inner coils and at least three active intermediate coils, all tightly wound, the outer active coil being low-stressed, the middle active coil highly stressed and the inner active coil still more highly stressed, whereby the outer active coil acts as a resilient casing to yieldably oppose unwrapping of the middle and inner active coils, said middle and inner active coils maintaining firm frictional contact with each other even after substantial wear due to the high stressing of said middle and inner active coils, and said spring being hot-wound with an

increasing helix angle from outer active coil to inner active coil, and then cold set, said spring being under relatively high radial compression at zero load due to the radial expansion during cold setting of at least one of said active coils at a greater rate than its enveloping adjacent coil.
